(57) **CLAIM**

I claim the ornamental design for a marine drift anchor, as shown and described.

DESCRIPTION

FIG. 1 is a top perspective view of a marine drift anchor showing my new design;

FIG. 2 is a bottom perspective view of the marine drift anchor of FIG. 1;

FIG. 3 is a side view of the marine drift anchor of FIG. 1, the opposite side being a mirror image of that shown;

FIG. 4 is a front view of the marine drift anchor of FIG. 1, the opposite rear being a mirror image of that shown;

FIG. 5 is a top view of the marine drift anchor of FIG. 1;

FIG. 6 is a bottom view of the marine drift anchor of FIG. 1;

FIG. 7 is a top perspective view of an alternative second embodiment of a marine drift anchor;

FIG. 8 is a bottom perspective view of the marine drift anchor of FIG. 7;

FIG. 9 is a side view of the marine drift anchor of FIG. 7, the opposite side being a mirror image of that shown;

FIG. 10 is a front view of the marine drift anchor of FIG. 7, the opposite rear being a mirror image of that shown;

FIG. 11 is a top view of the marine drift anchor of FIG. 7;

FIG. 12 is a bottom view of the marine drift anchor of FIG. 7;

FIG. 13 is a top perspective view of an alternative third embodiment of a marine drift anchor;

FIG. 14 is a bottom perspective view of the marine drift anchor of FIG. 13;

FIG. 15 is a side view of the marine drift anchor of FIG. 13, the opposite side being a mirror image of that shown;

FIG. 16 is a front view of the marine drift anchor of FIG. 13, the opposite rear being a mirror image of that shown;

FIG. 17 is a top view of the marine drift anchor of FIG. 13; and,

FIG. 18 is a bottom view of the marine drift anchor of FIG. 13.

The broken lines shown illustrate portions of the marine drift anchor that form no part of the claimed design.

1 Claim, 9 Drawing Sheets
